UNITED STATES PATENT OFFICE.

JOHN GOOD, OF BROOKLYN, NEW YORK, ASSIGNOR TO GOOD INVENTIONS CO., OF NEW YORK, N. Y., A CORPORATION OF NEW YORK.

LIQUID-FUEL BURNER.

1,379,180.

Specification of Letters Patent.

Patented May 24, 1921.

Application filed May 2, 1918. Serial No. 232,036.

To all whom it may concern:

Be it known that I, JOHN GOOD, United States citizen, residing in Brooklyn, New York, have invented the following-described

5 Improvements in Liquid-Fuel Burners.

The invention concerns the structure and mode of operation of liquid fuel burning apparatus and consists in the several features hereinafter described and more particularly pointed out in the claims, whereby such burners are adapted, among other things, to burn liquid fuel at a rapid rate with quick development of heat and to burn fuel in this manner with complete combustion in flame pipes and other closed passages and whereby they are adapted to be reliably ignited by spark without preheating of the air or fuel and whereby other advantages are obtained as will be hereinafter made apparent to those skilled in this art. The said objects are secured in the apparatus shown in the accompanying drawing by way of illustration of the principles of the invention.

25 Figure 1 is an axial section through the burner head and fuel receptacle structure; and

Fig. 2 is an elevation of the same on a smaller scale including the connection to the flame passage and fan blower.

The burner head is represented by an inclosure containing the mixing and combustion spaces and constituted in part by a Venturi tube 1 and a flame or combustion passage 2 which connects it to an open exhaust outlet indicated at 3 in Fig. 2. The combustion passage may, if required, be a pipe of relatively narrow dimensions and is so shown in the drawing. Air flow is created through the Venturi and such passage by a fan-type blower 4 which is illustrated as connected between the combustion space 2 and the outlet 3 but can be otherwise connected to produce the same effect or an equivalent flow. The fuel and air mixing means herein disclosed are specially suited for operation by low pressure differences and although other means for creating the air flow may be employed, fan-type blowers are preferred for illustration because they give ample delivery at adequate pressure differences and are economical of power. Liquid fuel is supplied from a receptacle 5 through a channel 6 leading to the fuel inlet orifice 7 in the throat region of the Venturi. An adjust-

able air tube 8 enters the fuel chamber in line with the orifice 7 and is adapted to admit air and mingle it with the fuel as it moves to said orifice. When the fan or suction means is in action a considerable reduction of pressure and a corresponding condition of high flow velocity occurs at the throat of the Venturi tube and serves to produce a more or less homogeneous, finely atomized and combustible mixture of the mingled air and fuel liquid arriving from the channel 6. It is preferred to transmit the pressure obtaining within the tube to the fuel receptacle 5—a function which is performed in the present case by the connecting pressure tube 9—so that the movement of fuel liquid to the orifice 7 occurs by the injector action of the air jet from the air tube 8, which jet is produced by virtue of said pressure reduction as will be evident. The outer end of the tube 8 is open to atmosphere. It will be apparent however, that the pressure connection 9 may be omitted, in which case the liquid will move to the throat directly by reason of the pressure reduction existing at that point, the fuel receptacle being in that case vented to atmosphere and the channel 6 being subject to regulation by screwing tube 8 in or out. The air entering by the tube 8 in any event serves to improve the atomization by breaking the liquid up prior to its entry into the flow of air through the throat of the Venturi tube.

Additional air enters the flame passage through the check valve inlet 10, the annular admission chamber 11 and the zone of air admission holes 12 formed in the divergent outlet wall of the Venturi. Such air enters the combustion inclosure under the same pressure difference as causes the flow through the throat of the Venturi tube, that is to say by the suction effect of the fan 4 in the present case, and joins the spray in the form of many penetrating air jets producing very thorough mixing and rapid combination with the fuel. The relation of the check valved entrance to the Venturi tube is such that under the action of the suction means or fan blower air enters the flame and combustion space at a predetermined rate with reference to the fuel which is suited to complete the combustion thereof within the burner structure.

Ignition of the fuel spray is by a spark plug 13 situated in the present case, in the

venturi end of the combustion space and operated coincidently with the starting of the suction flow through the apparatus. Reliability and quietness of ignition are assured by the action of the check valve 14, the movement of which is retarded by the dash-pot 15 so that it opens slowly when the fan is started in action and as the result of the operation of the fan. This retardation of the air supply to the zone of admission holes 12 results in an initial increase of the proportion of fuel in the spray mixture produced by the venturi which adapts it for prompt ignition by the spark so that by the time the air flow becomes normal the spray has been ignited and fluttering or explosions are thus avoided. The dash-pot is supplied with liquid through a pipe connection 16 with the fuel receptacle 5 and the ports through the dash-pot piston control the period of initial mixture enrichment, but this is only one of several ways in which such enrichment may be obtained for the purpose of ignition. When so enriched the position of the spark plug in the inclosure is not of material consequence. Its best position is between the throat and the zone of holes 12 as indicated in the drawing, but it may be placed anywhere in the path of the enriched spray and serves its function without explosive tendency. An igniting burner structure incorporating the principles above illustrated may have one or more fuel inlets 7 in its Venturi tube and even with a single inlet is adapted to burn liquid fuel at a high rate without the use of high pressures for atomization or supplying combustion-supporting air. For example, the fan illustrated operates on a pressure difference of about 10 inches of water and the combustion rate is adequate for portable forges and industrial furnaces of various kinds as well as for supplying heat to combustion engines as shown in my copending application Serial No. 149,998, filed February 21, 1917, and other uses. It is to be noted that the spring which seats the air valve 14 has the further function of controlling the degree of pressure reduction in the combustion space according to the suction effect and thereby correlates the rate of air flow to the rate of fuel supply to said space so that the mixture proportions are kept constant though the suction effect may vary and the burner is thus competent to burn properly at a variable rate. The valve of the auxiliary air entrance therefore, in the present case, controls the rate of fuel delivery to the end of preserving predetermined proportions.

Claims.

1. In liquid fuel combustion apparatus the combination of an ignition and combustion space, an electric igniter, a suction means in communication with the outlet of said space,

a Venturi-tube through which air flows to said space, a fuel channel conducting fuel to said tube at a rate maintaining combustible mixture proportions in said space and means whereby the fuel delivery therefrom is automatically increased to make the mixture proportions temporarily rich in fuel when the suction flow is started through said apparatus. 70

2. In liquid fuel combustion apparatus, 75 the combination of an ignition and mixing space, an igniter, a suction means connected to the outlet of said space, a Venturi-tube through which air flows to said space, a fuel channel conducting fuel to said space at a 80 variable rate adapted to maintain substantially constant mixture proportions therein, and means for automatically and temporarily increasing the fuel supply to make said mixture initially rich in fuel when 85 starting said suction means in action.

3. Inclosed combustion apparatus for liquid fuel comprising in combination, an ignition and mixing space, a suction means connected to the outlet of said space, a spark 90 plug, a Venturi-tube through which air flows to said space, a constant level liquid fuel receptacle, a passage leading fuel therefrom to the interior of said tube and adapted 95 to supply fuel at a rate maintaining combustible mixture proportions in said combustion space, means adapted to improve the thoroughness of the mixture in said space, and means for automatically making said mixture relatively rich in fuel when the suction means is started. 100

4. In liquid fuel burning apparatus, the combination of an ignition and mixing space, suction means for maintaining coincident inflow thereto and exhaust therefrom, 105 a liquid passage for conducting fuel to said space, an air entrance in atomizing relation to said passage and means for supplying liquid fuel and a small amount of air to said liquid passage. 110

5. In liquid fuel burning apparatus, the combination of an ignition and mixing space, means for maintaining coincident inflow thereto and exhaust therefrom, a Venturi-tube constituting a flow entrance to said 115 space, a liquid passage having an opening in the throat of said tube and means for supplying liquid fuel and a small amount of air to said liquid passage.

6. In liquid fuel combustion apparatus, 120 the combination of an ignition and combustion space, an electric igniter, a suction-producing means in communication with the outflow of said space, a Venturi-tube through which air flows to said space, a 125 fuel conducting passage having its outlet orifice in said tube and arranged to deliver fuel thereto at a rate normally keeping substantially constant proportions of fuel and air in said space, means for admitting a 130

small amount of air into the fuel in said passage and means for automatically making the mixture in said space temporarily rich in fuel to facilitate ignition when start-
5 ing.

7. In liquid fuel-burning apparatus an ignition and mixing space, means for maintaining coincident inflow thereto and exhaust therefrom, a Venturi-tube constituting a flow entrance thereto, an auxiliary flow entrance thereto, an air-opened valve controlling the flow through the latter entrance, and a fuel channel supplying fuel liquid to said space according to the condition established therein by said valve.
10

8. A liquid fuel burner comprising a Venturi-tube having a spark plug and a fuel entrance at its throat, a zone of air admission holes in its outlet portion and means 20 for creating air flow through the tube and holes.

9. An inclosed liquid fuel burner comprising a Venturi-tube having a fuel inlet at its throat region and adapted to produce 25 a mixture of liquid fuel and air, a closed flame passage intervening between said inlet and the exhaust outlet of the burner, means for supplying air and fuel to form said mixture of proportions adapted for complete combustion within said passage, a spark plug, and means for initially increasing the proportion of fuel in said mixture to facilitate ignition thereof by the spark plug.
30

10. Inclosed liquid fuel burning apparatus comprising a Venturi tube connected to a closed flame passage, means for creating air flow through said tube and passage, a fuel inlet orifice located in the throat 40 region of said tube, a liquid fuel supply and means for mingling air with the fuel moving therefrom to said fuel orifice.

11. Inclosed liquid fuel burning apparatus comprising a fuel receptacle, a flame 45 passage having a Venturi tube entrance and a fuel inlet at the throat of the tube connected to the fuel receptacle, a pressure con-

nexion between said tube and receptacle and an igniter for establishing non-explosive combustion in said passage.
50

12. In liquid fuel burning apparatus the combination of an ignition and mixing space, suction operated means for maintaining coincident inflow thereto and exhaust therefrom, a source of liquid fuel, a tube through which the fuel flows therefrom toward said space, an air entrance through which air enters in atomizing relation to the fuel delivered by said tube, a passage through which said fuel and said air pass to said space, means associated with said space for further subdividing said liquid fuel and distributing it therein, and an electric igniter in said space.
55

13. In liquid fuel burning apparatus the combination of an ignition and mixing space, suction operated means for maintaining coincident inflow thereto and exhaust therefrom, a source of liquid fuel, a passage conducting fuel therefrom to said space, a screw threaded air tube through which the suction effect in said space draws air into said passage for admixture with the liquid fuel therein, means whereby said liquid fuel and said air are further atomized and distributed in said ignition space and an electric igniter in said space.
60

14. In liquid fuel burning apparatus, the combination of an ignition space, suction means for maintaining coincident inflow thereto and exhaust therefrom, a liquid passage for conducting fuel to said space, an air entrance to said space coaxing with the outlet from said liquid passage, means for supplying liquid fuel and a small amount of air to said liquid passage and means whereby the fuel delivery from said liquid passage is automatically increased to make the mixture proportions temporarily rich in fuel when the suction flow is started through 90 said ignition space.
85

In testimony whereof, I have signed this specification.

JOHN GOOD.
